UNITED STATES PATENT OFFICE.

LAYTON M. PARKHURST, OF INDIANAPOLIS, INDIANA, ASSIGNOR, BY MESNE ASSIGNMENTS, TO GEORGE B. PITTS, TRUSTEE, OF CLEVELAND, OHIO.

VENDING-MACHINE.

1,383,996.

Specification of Letters Patent.

Patented July 5, 1921.

Application filed March 31, 1908, Serial No. 424,304. Renewed July 23, 1915. Serial No. 41,617.

To all whom it may concern:

Be it known that I, LAYTON M. PARKHURST, a citizen of the United States, residing at Indianapolis, in the county of Marion 5 and State of Indiana, have invented certain new and useful Improvements in Vending-Machines, of which the following is a specification, reference being had therein to the accompanying drawings.

10 This invention relates to improvements in vending machines, more particularly to machines for vending postage stamps, or the like.

One of the objects of my invention is to 15 provide a vending machine having one or more vending and money collecting units or sections, each including a lock box or substantial safety deposit box, whereby the maintenance of a large number of the 20 vending machines may be intrusted to the care of one party or a central office, to whom or to which the vending and collecting units are at intervals returned and from which 25 they are from time to time distributed, it being the intention that when one unit is removed from a machine for any purpose, it shall be replaced by another one.

Another object of the invention is to provide in a vending machine means for guiding 30 and controlling the movement of a disk or series of disks through a slot, whereby the actuator for the machine will be positively operated for each disk or series of disks.

35 Another object of the invention is to provide in a vending machine improved means for operating the lock and release devices for the machine, whereby the actuator will be positively operated.

40 Another object of my invention is to provide a vending machine having but few parts of simple construction, compactly arranged and readily assembled or disassembled, and which are substantially positive in 45 action and not readily gotten out of adjustment.

Other objects of my invention will be obvious from a machine shown in the drawings and hereinafter described for the purpose of illustration.

Figure 1 is a perspective view of an apparatus embodying my invention, illustrating the removal of one complete vending and money-receiving unit.

Fig. 2 is a front elevation of a machine 55 embodying my improvements.

Fig. 3 is a section on the line 3—3, Fig. 2.

Fig. 4 is a side elevation of one of the vending mechanisms, detached. 60

Fig. 5 is a front view of one of the vending sections.

Fig. 6 is an opposite side view of a vending section to the side view shown in Fig. 4.

Fig. 7 is a section on the line 7—7, Fig. 2. 65

Fig. 8 is a section on the line 8—8, Fig. 5.

Fig. 12 is a section on the line 12—12, Fig. 6.

Fig. 13 is a section on the line 13—13, Fig. 6.

Fig. 14 is a section on the line 14—14, Fig. 6. 75

Fig. 15 is a perspective view of the supplemental spring guard for the stamp strip.

Fig. 16 is a fragmentary side elevation 80 illustrating the operation of two coins in the coin slot.

In the drawings—

1 indicates as an entirety, a suitable housing or casing adapted to receive one or more 85 combined stamp vending and money collecting units 2. For illustration I have shown a casing 1 adapted to receive three of the said units 2. The casing or housing consists preferably of a bottom wall 3, side 90 walls 4, 5, a top wall 6, a front wall 7, and a rear wall or door 8, suitably hinged at 8' to the side wall 5 or otherwise arranged to permit easy access to the interior of the casing, when desired. Within the casing, the 95 detachable unit sections 2 are arranged side by side, each unit being intended to carry and vend a given number of stamps of one denomination, say one thousand. That is, the first unit on the left, as illustrated in Fig. 2, may be designed for vending one cent stamps, the next unit for vending two cent stamps, and the third for vending five cent stamps, it being understood that the construction and arrangement of each unit section is readily adaptable for vending a stamp of any denomination. 100

9, 10, are guides and spacing bars secured 105

to the bottom wall 3 of the casing, and 11 and 12 are guides and spacing bars, the former secured to the side wall 4, and the latter to the side wall 5 of the casing. The 5 purpose of these guides and spacing bars is to properly position the vending and money-receiving units relative to each other within the housing or casing 1.

Each unit 2 includes a box or casing 14, 10 preferably made of metal and rectangular in form. This box or case has side walls 15, 15', a front wall 16, top and bottom walls 17, 18, and a detachable rear wall 19. The detachable rear wall 19 may be fitted to 15 the side walls in any suitable manner. For illustration I have shown the side walls carrying at their rear edges outwardly extending transverse ribs 15^a. At each side the rear wall 19 is flanged, as indicated at 19', 20 and longitudinally grooved at 19^a to receive one of the ribs 15^a on a side wall. At its upper end the rear wall 19 carries an inwardly turned lip 19^b arranged to overlap the top wall 17 of the box. The bottom wall 25 18 may be extended rearwardly at 18', beyond the side walls, and the rear wall 19 is recessed at 19^c to fit over the said extension 18'. A suitable lock 20 is employed for locking the detachable wall of the box in position.

The inside of each safety box 14 is divided into an upper and a lower compartment by means of a slide or platform 21 supported by inwardly turned ribs 22, 22', on the side 35 walls of the box. The lower one of these compartments is a cash box. The upper compartment is subdivided into two parts by a vertically disposed partition 23, preferably carried by the platform 21. Upon 40 one side of this partition 23 is arranged the stamp feed mechanism of the unit, and upon the other side the coin controlled mechanism for actuating the stamp feed mechanism.

Of the stamp feed mechanism, 24 is a 45 stamp box secured to or formed integral with the partition 23 and extending at one side thereof. 25 is an arbor or shaft, preferably stationary, upon which may be mounted a roll 26 of postage stamps. 27 is 50 a guard plate axially recessed at 27' and fitted loosely upon the arbor 25. 28 is a stamp strip guide carried by the guard plate 27. This guide preferably consists of two pins 28', 28^a, extending inwardly from the 55 guard plate 27 and arranged to have directed between them the strip of stamps fed from the roll of stamps 26 within the box. 29 is a transverse slot through the top of the box 24, through which the stamp strip 60 is led. As the guard plate 27 is loose upon the shaft 25, the guide 28 is free to play back and forth slightly within the box 24 and readily accommodate itself to the stamp strip so as to prevent the stamp strip engaging with and rubbing and wearing against

one of the edges of the walls of the slot 29. 30 is a cover or end plate for the stamp box fitted on to the screw threaded end of the shaft 25.

31 is a delivery member or cylinder. The 70 cylinder may be provided with an end wall. 32 is a shaft or stud extending laterally from the end wall of the cylinder, preferably formed integral therewith, and mounted in a bearing 33 in the partition 23. This bearing is formed through the partition 23 and an annular boss 31' thereon, which latter is fitted into an annular recess 31^a in the stamp cylinder. 34, 35, 36 are peripheral grooves in the said stamp cylinder which at each 80 side is slightly flanged as indicated at 37. At regular intervals these flanges are notched or recessed, as indicated at 38, the notches being spaced apart on the said flanges the distance occupied by one of the stamps to be 85 vended on the periphery of the stamp cylinder. Across the periphery of the stamp cylinder are arranged lines of strip piercers or perforating points 39, each line adjacent to a pair of notches 38 which are opposite to 90 each other on the stamp cylinder. These lines of perforating points 39 are, likewise, spaced apart on the periphery of the stamp cylinder the distance occupied by one stamp on the periphery of the cylinder.

40 are pressure rolls for laying the strips of stamps evenly over the periphery of the stamp cylinder and between the flanges 37 thereon, and also for pressing the stamp strips over the perforating points so as to 100 cause the latter to pierce the strip. Each of these pressure rolls 40 is loosely mounted on a transverse shaft 41 carried by a frame 42. This frame 42 is normally pressed upwardly so as to force the pressure rolls 105 against the periphery of the stamp cylinder by means of a flat spring 43, one end of which is secured to the bearing plate 42 and the other to a lug or projection 44 carried by the partition 23. Each pressure roller 110 40 has a peripheral groove 40' adapted to receive, one after the other, as the stamp cylinder is rotated step by step, the perforating points on the periphery of the stamp cylinder which are in the same vertical plane 115 with the groove 40'. 45 is a guard plate extending about the circumference of the stamp cylinder at the top thereof. At its lower front end this guard plate carries a strip cutting or severing knife 46, which may be 120 formed integral with the guard plate, if desired. At either side, this knife 46 is adapted to enter one of the recesses 38 in the flanges 37 on the stamp cylinder. 47 is a spring secured at one end to the guard plate 45, and at its other end to a lug or projection 48 on the partition 23, this spring tending normally to press the guard plate 125 downwardly against the flanges on the stamp cylinder. Beneath the guard plate 45 is 130

arranged a supplemental spring guard 49 having spring members 49', each arranged in the vertical plane of one of the peripheral grooves 34, 35, 36 on the stamp cylinder and 5 adapted to maintain the stamp strip pressed firmly against the periphery of the stamp cylinder. These spring fingers 49' are connected at their lower ends to a guard plate 49^a interposed between the end 45' of the 10 guard 45 and the pressure rollers 40. This plate 49^a rests lightly at either side upon the flanges 37 on the stamp cylinder, and prevents the stamp strip 26 from riding up on either of said flanges and getting out of 15 proper adjustment. The guard 45 prevents the spring fingers 49' from getting out of position.

50 is a deflecting plate for directing the stamps away from the stamp cylinder 31 20 and out of the unit 2 which carries them. It preferably consists of a piece of spring metal having a plurality of fingers 50', each arranged to enter one of the peripheral grooves 34, 35, 36 in the stamp cylinder, so 25 that the free ends of these fingers will be beneath the free end of the stamp strip as the latter is rotated on and fed forward with the stamp cylinder. 51 is a transverse lug or extension carried by the platform 23 and 30 to which the said stamp deflecting plate 50 is secured.

As hereinbefore stated, the coin controlled mechanism is arranged on the opposite side of the partition 23 from the stamp feeding 35 mechanism. It comprises a locking cam 52 the periphery of which has a plurality of identically similar cam surfaces 53, equal in number to the number of stamp receiving sections on the stamp cylinder 31 and correspondingly positioned relative to the axis 40 of the shaft 32. This cam wheel 52 is fitted, in any suitable manner, to the shaft 32 to turn therewith. At the bottom of each of the recesses 53 is a notch 54 adapted to receive the free end of a locking dog 55 on a 45 release rod 56. This release rod 56 is pivotally connected at its lower end to the partition 23, as indicated at 56'. 57 is a spring secured at 57' to the partition 23 and having 50 its free end bearing against the release rod 56 and normally pressing its end carrying the dog 55 toward the locking cam 52.

58 is a ratchet drive wheel suitably secured to the shaft 32 to turn therewith. Its 55 periphery is studded with a plurality of teeth 59, equal in number to the number of locking recesses 54 on the locking cam 52, and each tooth 59 arranged to correspond with one of the said locking recesses on the 60 locking cam.

60 is a bearing and guide bracket secured at 61 to the partition 23 and having a bearing opening at 62 for the shaft 32, and a vertically disposed guideway at 63. 64 is a 65 main operating rod having its upper end

fitted to and guided by the guide 63 on the bracket arm 60, and its lower end extending through a hole 21' in the platform or division plate 21. This operating rod carries a laterally projecting arm 65, preferably bifurcated to receive the lower end of a driving pawl 66, the upper end of which is toothed at 66' to engage with the teeth 59 on the ratchet 58, one after the other. The driving pawl 66 is pivotally connected at 66^a 75 to the arm 65. 67 is a spring secured at 67' to the rod 64 and having its upper end normally pressing outwardly on the lower end 66^b of the oscillatable pawl 66, so as to normally press the tooth 66' toward the ratchet 80 wheel 58. The innermost section 65' of the lateral arm 65 on the main operating rod 64 carries a slide 68 arranged to bear at its inner edge against the partition 23 and to keep the upper end of the rod 64 suitably 85 spaced from the ratchet wheel 58. 69 and 70 are lateral extensions carried by the rod 64, each of them being preferably bifurcated to receive the reduced end of one of the oscillatable links 71, 72, each of which is 90 pivoted to one of said extensions. Each of these links 71, 72 has its upper end reduced in thickness, as indicated at 71', 72', and fitted to oscillate in a slot in one of the slotted arms 73, 74 carried by the main operating rod 64. 75 is a coil spring preferably surrounding the rod 64 between the lateral projections 69, 70 thereon and the division plate 21, and tending to normally press the rod 64 upwardly, as indicated in Fig. 4. 76 100 is a plate, grooved as indicated at 77, to form with the partition 23 a coin passageway 78, the upper end of which terminates in a coin-receiving slot 78', and the lower end of which registers with a coin-discharge slot 79 105 in the division plate 21. 80 and 81 are slots formed in the plate 76 and each adapted to receive one of the pins or projections 82, 83 which extend inwardly from the links 71, 72, respectively. The slots 80 and 81 are so 110 shaped that, as the main operating rod 64 is depressed, the walls of the slots first guide the pins 82, 83 on the links 71, 72, toward the longitudinal axis of the rod 64, thereby simultaneously drawing together the upper 115 ends of the links, as shown in Fig. 16, and then vertically downward, tending to maintain the links 71, 72 with their upper ends adjacent to the rod 64 and with the pins 82, 83 in the coin passageway 78. 84 is a coin-actuated element adapted to throw the release rod 56 and the locking pawl 55 thereon, 120 away from the locking cam 52. I prefer to have this release rod-actuating element 84 an anti-friction roller. This roller 84 has 125 an axial aperture 84'. 85 is a pin extending through the aperture 84' into the metal of the partition 23 and the coin guide plate 76 at either side of the roller. The metal of the coin guide is recessed at 86 to permit the 130

roller 84 to be projected through the recess 86 and have its periphery engage with the front wall of the release bar 56. The diameter of the pin 85 is considerably less than 5 the diameter of the aperture 84' through the anti-friction roller 84, so as to permit lateral motion of the roller relative to the said pin, while at the same time retaining the roller in the recess 86. Suitable operating mechanism 10 should be provided within the casing 1 for actuating, that is, depressing, the main operating rod 64. For illustration I have shown such mechanism adapted to be actuated by hand; although it will be understood 15 that, if desired, automatic power mechanism may be employed. 87 is a bracket secured to the top 6 of the casing 1. 88 is a lever pivoted at 88' to the said bracket 87 and having an operating handle 88" which projects out of the case through a vertical slot 89 in the front wall thereof. 90 is a rod pivotally connected at 90' to the lever 88. This rod extends through a hole 91 in the top of the box or case beneath the lever 88. 20 The upper end of the operating rod 64 may be pointed, as indicated at 90^a, and the lower end of the rod 90 may be recessed, as indicated at 90^b to receive the pointed ends of the operating rod 64. As shown in the 25 drawings, the casing or housing 1 carries as many hand operating devices, such as the one just described, as there are units in the case,—one for each unit.

I have found it desirable to provide each 30 unit or section 2 with an automatically actuated safety attachment for preventing the introduction into the coin passageway 78 of a coin or coins after the unit is practically exhausted of stamps, or when the stamp strip breaks between the stamp box 24 and the stamp cylinder 31. Of this safety 35 attachment, 91 is a bracket carried by the partition 23. 92 is a bell crank lever pivotally connected at 92' to an arm on the said bracket. 93 is a stop rod pivotally connected at 93' to one arm of the bell crank lever 92, and having its other end extending through a hole 93^a in the partition 23, and arranged to be projected into and withdrawn 40 from the coin passageway 78 at the entrance thereto. 94 is a rod pivotally connected at 94' to the other arm of the bell crank lever 92, extending through a passageway 94^a in the bracket 91, and having secured to its free end a bearing block 95 carrying a pivotally mounted anti-friction roller 96. 97 is a coil spring encircling the rod 94, interposed between the bracket 91 and the bearing frame 95 and adapted to normally force the rod 94 rearwardly so as to project the rod 93 across the coin passageway 78. 98 is a bracket secured to the stamp box 24 and having an upwardly extending wall 98' with a hole 98^a therethrough in line 50 with the anti-friction roller 96, and through

which the latter may be projected. Normally, when the unit is in readiness for operation and the stamp strip extends from the stamp box 24 to the stamp cylinder 31, the roller 96 rests relatively lightly against 70 the said strip. Should the end of the stamp strip pass the said roller, or the strip be severed between the stamp box and the stamp cylinder, or the strip in any wise be removed from between the said roller and 75 the slot 98^a in the bracket 98, the spring 97 will force the rod 94 rearwardly, the roller 96 entering the slot 98^a, and the bell crank lever 92 will be rocked so as to project the rod 93 across the mouth of the coin passageway 78.

The front wall 16 of each unit 2 is slotted at 99 to register with coin slot 78' of the coin actuated mechanism within the unit, and cut away at 100 to allow for the delivery from the unit of the stamps. The front wall 7 of the casing 1 is provided with as many openings 101 through it as there are units 2 or spaces for them within the casing. Each of these openings 101 is preferably arranged to expose both the coin slot 99 and the stamp delivery opening 100 of a unit.

In operation, a roll of stamps 26 is placed upon the arbor 25 in the stamp box 24 and 95 the outer end of the strip of stamps is directed upwardly and out through the slot 29 in the top of the stamp box, and between the stamp cylinder 31 and the presser rolls 40. The guard plate 27 is placed in position with the stamp strip leading between the guides 28', 28^a on the guard plate, and the cover 30 of the stamp box is then placed in position. In directing the stamp strip onto the stamp cylinder and between 100 it and the pressure rollers 40, care should be taken to have the perforating points on the stamp cylinder, which are projected into the grooves 40' on the pressure rollers 40, pierce the stamp strip on the transverse line 105 of connection between two stamps of the strip. The release rod 56 may be then thrown so as to withdraw the locking pawl 55 from the periphery of the locking cam 52, and the stamp cylinder may be rotated 110 until the free edge of the first stamp of the strip appears at the cutting knife 46. The machine is then ready for operation and may be inserted into its box or case and the latter placed in its proper position in the 115 casing or housing 1.

Assuming that the apparatus is adapted to deliver a two cent stamp upon the introduction through the coin slot of two pennies, the lower penny of the two will engage with 120 the periphery of the roller 84 which extends into the coin passage 78, and the further descent of the penny through the coin passage will be arrested. The descent of the second penny through the coin passage 130

way will be stopped by its engagement with the first penny. Having introduced the two pennies, the operator presses downwardly on the operating handle 88^a, and through the 5 thrust rod 90 imparts a downward motion to the main operating rod 64; as this rod 64 is depressed, the walls of the grooves 80 and 81 direct inwardly the pins 82 and 83 on the links 71, 72, respectively, until they are at 10 points above and engage with the periphery of the uppermost penny in the coin passageway 78. The further downward movement of the rod 64 and links 71, 72 causes the periphery of the lower penny to press outwardly and away from the coin passageway 15 the release rod-actuating roller 84, simultaneously through the said roller imparting an outward throw to the release rod 56, which continues until the locking dog 55 is 20 out of engagement with the walls of the last locking recess 54 on the locking cam 52 which it entered. The feed pawl 66 now engages a ratchet tooth 59 on the ratchet wheel 58 and pulls downwardly thereon, imparting 25 a rotary movement to the ratchet wheel, the locking cam, and the stamp cylinder. The two pennies drop through the slot 79 into the cash box, and the locking dog 55 rides around on one of the cam surfaces 53 30 on the cam wheel 52 until it drops into the cam recess 54 at the end of said section, thereby again locking the ratchet wheel from further rotation, the release rod simultaneously pressing the roller 84 through the 35 slot 86 until its periphery again projects into the coin passageway 78. The rotation of the ratchet wheel 58 at each step is calculated to impart a rotary motion to the shaft 32 which will turn the stamp cylinder 40 31 angularly a distance to deliver one stamp through the stamp discharge opening 100.

When it is desired that but a single coin shall operate the apparatus, the vertical distance between the release rod-operating element 84 and the pins 82, 83 on the links 71, 72 is shortened. This I have illustrated in Fig. 9. With the parts thus correlated, a single coin when introduced into the coin passageway 78 has its descent therethrough 45 arrested by engagement with the roller 84. When the operating rod is now depressed, the pins 82, 83 engage with the periphery of the single coin and force the coin downwardly through the coin passageway, at the 50 same time expelling the roller 84 therefrom and causing the release of the dog 55 from the locking cam 52.

A machine constructed in accordance with my improvements is capable of construction 55 so as to preclude its operation with other than accurately shaped and sized coins or disks. The coin slot 78' for each unit may be accurately dimensioned so as not to permit the introduction of coins or disks 60 above a certain thickness and diameter. The

rollers 84 may be constructed and mounted relative to the release bar 56 so as to require to be pressed outward a predetermined distance before it will move the free end of the release rod a sufficient distance to withdraw 70 the dog 55 from a cam locking cam recess 54 and permit the rotation of the locking cam 52 and the delivery of a stamp. If the disks with which it is attempted to operate the machine are too small in diameter, the 75 release element 84 will not receive sufficient throw to actuate the release rod 56 and withdraw the dog 55 from a locking cam recess 54.

My invention contemplates the desirability 80 of vending stamps from what may be considered safety deposit boxes, each of which boxes or units is readily removable from the main vending case when the stamps in it are exhausted, or for any other purpose; it being 85 the intention that such unit be returned to a central station, office or party to be held responsible, not only for the loading of the units with stamps, but also for the care of the funds or money collected in the units. 90 This system, it will be understood, possesses the great advantage of placing all of the responsibility for the distribution of stamps through the machines and the care of the money taken in return, upon a single individual or central station. The many advantages of such a system will be readily appreciated where large installations of the machines are made and have to be maintained. Take for example, the use of the 100 machines in connection with a post office department in a large city. The handling of great numbers of stamps is necessitated, and with all the earlier stamp vending machines of which I am aware, the stamps must 105 be intrusted to some party to be distributed to the machines by actually taking the stamps in rolls of sheets to and putting them in the machines. Also the moneys collected by the machines are taken from boxes or 110 receptacles in the machines by a trusted party for return to the post office department. With my apparatus it is intended that one party or division shall be made responsible for both the filling of the vending 115 and collecting units with stamps, and the removal and care of the money collected in each unit. All this may be accomplished at a central point, the units—substantially safety deposit boxes—being collected from 120 the various vending cases from time to time and brought to the central point for removal of money collected and refilling with stamps.

The keys for the unit sections may all be retained in the possession of the division or 125 party having charge of this work. By thus making one person or division responsible for the maintenance of the machines, the chances of loss of money and stamps is very greatly minimized over those incident to the earlier 130

systems, in which the stamps in rolls or sheets have to be taken to the vending machines, and loose money taken from the machines. The responsibility placed on the 5 caretakers of the vending casings or housings and the distributors and collectors of the units is reduced to substantially nothing more than the mere handling of the units or safety deposit boxes themselves. These 10 distributors and collectors never have to touch the stamps or the money collected in the machines; in fact, they could not do so without breaking open the units, which would be a criminal offense.

15 It will be understood that by a mere variation of the size of the coin passageway and incident variation necessitated in size of correlated parts, units may be constructed for operations with coins of different values 20 and sizes. In the drawings, for purposes of illustration, the three units shown are intended for vending one, two, and five cent stamps, respectively, as hereinbefore stated.

The coin-actuated and stamp feed mechanism is confined in a relatively small space 25 and consists of a small number of parts, all of which is quite essential to an apparatus intended to be operated as mine is, namely, that the units from time to time be removed 30 and replaced by others, while the removed ones are being emptied of money and refilled with stamps. All parts of the machine are readily accessible and may be quickly and easily assembled.

35 The coin passage in each machine may be filled up with coins, if desired by the operator, and then the operating handle 88^a operated the number of times which the coins introduced will buy stamps of the denomination desired. This may be done without 40 danger of more than the requisite number of coins being deposited into the cash box of the unit at one operation of the handle 88^a, as the pins 82, 83, after engaging and 45 pressing downward a coin or a plurality of coins, prevent any coins above them in the coin passageway from getting past them, until after they have been again elevated and the stamp cylinder re-set.

50 My disclosures and description herein are intended to be purely illustrative and not in any sense limiting, as many alterations in the construction and many apparently widely differing embodiments of my invention 55 will suggest themselves to those skilled in the art of making coin-controlled apparatus without departing from the spirit of my invention.

Furthermore, while I have herein referred 60 to my invention more particularly as applied for the purpose of vending stamps, it will be understood that it is equally suitable and adaptable for the purpose of vending tickets, or the like. In fact, a machine embodying 65 my invention may be advantageously em-

ployed for vending railway tickets, theater tickets, tickets for amusement parks and the like, soda-checks or coupons, thereby dispensing with the services of ticket sellers, who are now generally employed for such 70 purposes.

No claim is made herein to the divisional 75 subject-matter relating to the use of a plurality of coins to effect an operation of the machine, as such subject-matter is covered by my divisional application Ser. No. 460,593, filed April 11, 1921.

What I claim is—

1. The combination of a support having a coin chute, a movable member, means for locking said member against movement, a movable device normally projecting into the coin chute and serving as an arrester therein for a coin, said device having operative engagement with and bodily movable laterally 85 to actuate said locking means, and means for moving a coin past said device.

2. The combination of a locking mechanism having a dog, a coin chute formed with an opening at one side, a coin arresting device arranged to engage with said dog, normally projecting through the opening into the coin chute and bodily movable laterally to operate said dog, and means for moving the coin past said arresting device.

3. In mechanism of the class described, the combination of a locking mechanism having a dog, a coin chute, a disk normally projecting into the path of a coin through said chute and having operative engagement 100 with said dog, said disk being rotatable and laterally movable, and means for moving the coin past said disk.

4. In a coin controlled apparatus, the combination of a movable member, a device arranged to lock and release said member, a coin controlled mechanism for operating said device, comprising a coin guide, a coin stop movable into and out of the path of movement of the coin through said guide 105 and arranged to operate said lock and release device, and means for forcing the coin past said stop to expel the coin from said guide and substantially simultaneously release said locking device and operate said 110 member.

5. In a mechanism of the character described, the combination of a casing including a coin guide, a movable control member, a dog for locking and releasing said control member, a laterally movable, rotatably mounted element normally projecting into the path of the coins through said guide for arresting coins therein and arranged to operate said dog, and means for moving said 125 coins past said arresting element, substantially simultaneously expelling said coin, releasing said dog and operating said control member.

6. In a coin controlled machine, the com-

- bination with a casing and a coin chute, of a control member, an operating member, a pawl connected to said operating member for operating said control member, means for locking said control member against movement, a coin arrester arranged in the path of movement of the coin through said chute and having engagement with said locking means, said arrester being bodily movable laterally by the coin to release the locking means from said control member, and means actuated by said operating member and operating through a coin arrested by said arrester to move the latter.
- 15 7. In a coin controlled machine, the combination of a casing including a coin guide, a cam provided with a plurality of notches, a dog engaging with said notches for controlling the operation of the cam, a coin arresting device projecting into the coin guide, said device being operatively connected with and bodily movable laterally, to operate said dog, an operating member, connections between said operating member and said cam for operating the latter upon the release of the dog therefrom, and a device arranged to be moved by said operating member to force a coin past the said arresting device, move the latter laterally and operate said dog.
- 30 8. In an apparatus of the character described, the combination of a pair of ratchet wheels rigidly secured together, a dog normally arranged to engage with one of said ratchet wheels and lock it against rotation, a movable member provided with a pawl arranged to engage and operate the other ratchet wheel during movement of said member in one direction, a coin guide, a coin stop movably mounted in said coin guide and arranged to operate the said dog, and means operated by said movable member and arranged to engage with a coin introduced in the coin guide for forcing the coin past said stop, move the latter laterally and disengage the said dog from the adjacent ratchet wheel.
- 45 9. In a mechanism of the class described, the combination of a lock mechanism, a movable member, a coin chute, an arrester arranged intermediate the ends of the chute for arresting a coin, an operating member, a coin engaging device connected to said operating member and normally arranged out of the path of the coin through said chute, means for moving said coin engaging device into position to engage said coin as said operating member is operated and move it past said arrester and through the latter release said lock mechanism, and means connected to said moving means for operating said movable member.
- 60 10. In mechanism of the class described, the combination of a coin chute, an arrester arranged intermediate the ends of the chute for arresting a coin, an operating member, a coin engaging device pivotally connected to said operating member and normally arranged out of the path of the coin through said chute, and means for moving said coin engaging device into position to engage said coin as said member is operated and move it past said arrester.
- 65 11. The combination of a coin chute, a device extending into the chute intermediate its ends and movable by a coin to actuate a locking mechanism, a member disposed at one side of said chute between its coin receiving end and said device for moving a coin into engagement with and past said device, means for directing said coin moving member into engagement with a coin in said chute, and means for moving said coin moving member endwise of the chute after it has engaged a coin therein.
12. In mechanism of the class described, the combination of a coin chute, locking means including a dog, a device extending into said chute and arranged to be actuated by a coin to release said dog from said locking means, and a coin engaging member normally disposed at one side of said chute and movable in the plane of a coin at an angle to the coin chute into engagement with the coin and then longitudinally of the chute to force the coin therethrough past said dog actuating device.
13. In a coin controlled machine, the combination of a casing including a coin guide, a cam provided with a plurality of notches, a dog engaging the said notches for controlling the operation of the cam, a coin arresting device projecting into the coin guide and arranged to operate said dog, an operating member, ratchet mechanism between said operating member and said cam for operating the latter upon the release of the dog therefrom, a coin engaging device movable with said operating member, said device being normally arranged out of the path of the coin, and means for controlling the operation of said device to cause it to move into engagement with a coin when said operating member is actuated.
14. The combination of a support having a coin chute, a movable member, means for locking said member against movement, a movable device normally projecting into the coin chute and serving as an arrester therein for a coin, said device being in operative engagement with said locking means, whereby it will be moved by a coin to release the locking means from the movable member, and means for moving a coin past said device to actuate said locking means, said coin moving means including a movable element normally arranged out of the path of movement of the coin and means for moving said element into position for engagement with the coin.

15. In a coin controlled machine, the combination of a casing including a coin guide, a cam provided with a plurality of notches, a dog engaging with said notches for controlling the operation of the cam, a coin arresting device projecting into the coin guide and arranged to be actuated by a coin to operate said dog, an operating member, connections between said operating member and 10 said cam for operating the latter upon the release of the dog therefrom, and a device connected to and movable with said operating member, said device being normally arranged out of the path of the coin but movable into engagement with a coin as said operating member moves to force the coin past said arresting device, and through the latter operate said dog.
16. In a machine of the character described, the combination of a movable member, a coin controlled mechanism for controlling the movement of said member, the said mechanism comprising a rotatable disk, a dog arranged to engage with and lock and 25 release said disk, a coin guide, a combined coin stop and dog operating element movable into and out of the path of movement of the coin through said guide and arranged to operate said dog, means arranged to enter 30 said guide to engage with the periphery of the coin therein to move said coin through said guide past said element and substantially simultaneously expel said coin and operate said dog, and a pawl operated by said 35 coin moving means for operating said movable member upon the release of said dog from said disk.
17. In mechanism of the class described, the combination of locking means, a coin 40 chute, a device in said chute arranged to be actuated by a coin to release said locking means, and a pair of members for moving a coin in said chute past said device, said members being normally disposed at opposite 45 sides of said chute but arranged to be moved toward each other for engagement with and operation of the coin.
18. In a coin controlled machine, the combination of locking means, and coin controlled mechanism for releasing the said locking means including a coin guide having a passageway for coins therethrough and cam slots for directing coin engaging pins into and out of said coin passageway, a 50 coin stop and lock releasing element arranged to be moved into and out of the said coin passageway, coin engaging pins extending through said cam slots in the coin guides, and means for moving said coin engaging 55 pins whereby they enter said coin passageway, engage a coin therein, force it against said coin stop and expel the latter from said coin passageway, and substantially simultaneously release said locking means.
- 60 65 19. In a coin controlled mechanism, the

combination of locking means, and coin controlled mechanism for releasing said locking means, including a coin guide having a coin passageway therethrough and a cam slot through one wall of said guide arranged to 70 direct a coin engaging pin into and out of the coin passageway, a reciprocatable rod, a link pivotally connected at one end to said rod, a coin engaging pin at the free end of said link and arranged in said cam slot in 75 the coin guide, a coin lock releasing element arranged to be moved into and out of the coin passageway in said guide, and means for reciprocating said rod.

20. The combination of a support having 80 a coin chute, a movable member, means for locking said movable member, a device extending into said coin chute and arranged to be operated by a coin to release the locking element of said locking means, and 85 means for moving a coin past said device to operate it, said moving means including a plunger, a link pivotally connected thereto and carrying a coin engaging member normally arranged out of the path of the coin 90 through said chute and means for swinging said link about its pivot to cause said coin engaging member to engage the coin in the chute.

21. The combination of a support having 95 a coin chute, a movable member, means for locking said movable member, a coin arrester in said coin chute arranged to be operated by a coin to release the locking element of said locking means, and means for moving a 100 coin past said arrester to operate it, said moving means including a plunger, a link pivotally connected thereto and carrying a coin engaging member normally arranged out of the path of the coin through said 105 chute and a guide for swinging said link about its pivot to cause said coin engaging member to engage the coin in the chute.

22. In an apparatus of the character described, the combination of a casing having 110 a wall movable to permit access to the interior thereof and a series of units each comprising a box having a wall movable to permit access to the interior thereof and arranged to be locked, and a coin control mechanism mounted in each unit, including an operating member, and means carried by the casing for operating each operating member separately.

23. In a vending machine, the combination 120 of a casing, lock boxes removably mounted within said casing, coin controlled mechanism arranged in each one of said lock boxes, and means carried by said casing for actuating the coin controlled mechanism in each of 125 said lock boxes.

24. In a vending machine, the combination 130 of a casing, lock boxes arranged within and readily removable from said casing, each lock box comprising two compart-

ments, one of which is a money-receiving compartment, coin controlled mechanism arranged in the other one of said compartments, and means arranged in said casing 5 for operating the coin controlled mechanism in each of said lock boxes.

25. In a vending machine, the combination of a casing, a plurality of vending and money collecting units arranged within the 10 said casing, each of said units comprising a lock box, and coin controlled mechanism arranged within said box, and means carried by said casing for operating the coin controlled mechanism in each of said units.

15 26. In a vending machine, the combination of a casing, a plurality of units arranged within said casing, each of said units comprising a lock box, a slide horizontally disposed and guided in said lock box to divide it into two compartments, the lower 20 one of which is to receive coins, and coin controlled mechanism arranged upon said slide, and means carried by said casing for operating the coin controlled mechanism in 25 each of said units.

27. In a vending machine, the combination of a box or unit having side, front, and rear walls, one of said walls being movable to permit access to the interior of said box, 30 the opposite inner faces of two of said side walls being provided with guides, a frame arranged to be inserted into and removed from said box and slidably supported on said guides, a partition carried by said 35 frame and provided with a bearing, and a coin controlled mechanism mounted on said partition, said mechanism including a rotatable shaft mounted in said bearing and controlled by said mechanism.

40 28. In an apparatus of the class described, the combination of a coin receiving chute having a movable release member extending thereinto and arranged to be actuated by a coin passing through the chute, a device 45 normally disposed outside of said chute between its coin receiving end and said member, and means for moving said device into said chute rearward of the coin therein required to actuate said member, whereby any 50 coins in said chute in addition to the one actually required to effect the actuation of said release member are prevented from passing through said chute while said movable release member is being actuated.

55 29. In an apparatus of the class described, the combination of a release device for a movable member, a chute adapted to receive coins and guide them into engagement with said device, and operating means including a swingably mounted member movable into position successively to engage

with and move coins in the chute past said release device to operate it and prevent more than one coin to engage with or pass by the latter during each operation of said operating means. 65

30. In an apparatus of the class described, the combination of locking means, a coin controlled mechanism including a chute adapted to receive coins and a device in said 70 chute arranged to be actuated by a coin while passing therethrough to release the locking element of said locking means, and a pair of elements disposed at opposite sides of said chute and arranged to move there- 75 into rearward of the coin required to actuate said release device to move the coin past said device and prevent additional coins from passing through the chute during the operation of said pair of elements. 80

31. In an apparatus of the class described, the combination of a locking mechanism, a coin arrester arranged to be actuated by a coin to control the operation of said mechanism, a chute adapted to receive a plurality 85 of coins and guide them into engagement with said arrester, one after the other, an element normally arranged out of the path of the coins through said chute but movable into said chute between the coin required 90 for each operation of said arrester and the remaining coins in the chute to engage with and move the coin on one side of said element past said arrester and to prevent the coins on the other side of said element from 95 engaging with or passing by said arrester during each operation of said element.

32. In an apparatus of the class described, the combination of a release device arranged to control a movable member, a chute adapted to receive a plurality of coins and guide them into engagement with said release device, one after the other, and operating means including a pair of swingably mounted coin engaging members normally arranged out of the path of the coins through said chute but movable into position to engage with and move the coin therein past said device to actuate it and prevent the coins not actually required for a single actuation of said device to engage with or pass by it during each operation of said operating means, and means for controlling the swinging movement of said coin engaging members into and out of the path of the 110 coins through said chute. 115

In testimony whereof I affix my signature, in the presence of two witnesses.

LAYTON M. PARKHURST.
